UNITED STATES PATENT OFFICE

FRAZER W. GAY, OF NEWARK, NEW JERSEY

ELECTRICAL TRANSFORMER SYSTEM

Application filed November 9, 1929. Serial No. 405,935.

This invention relates in general to electrical transformer systems, one object of the invention being to provide a novel and improved transformer system including means for changing the magnetic density by a simple automatic switching operation and without throwing the transformer or any of its windings out of the circuit.

The character and objects of the invention may be better understood by a consideration of the fact that most transformer systems operate for long periods of time at only light loads which are far less than the peak loads which the system must be designed to carry. The loads on such transformer systems may vary from a maximum or peak of five hundred thousand kilowatts (500,000 kw.) on some days to a minimum of one hundred thousand kilowatts (100,000 kw.) during nights, the average load during the year being around two hundred fifty thousand kilowatts (250,000 kw.).

Assuming as indicated, that the system has transformers to carry approximately four million five hundred thousand kilovolt amperes (4,500,000 kva.), the system will draw continuously approximately fifteen thousand kilowatts (15,000 kw.) in core losses. During minimum load periods, the transformer core losses constitute a very appreciable part of the load, and it is evident that any system that will greatly reduce these light load core losses, will produce substantial economies in the operation of the system.

While the power lost by the large public utility companies in transformer core losses is a large item, during light load periods the cost of such incremental power is only a small fraction of a cent. However, there are many industrial companies where losses per kva. of installed capacity are much greater, and the cost of incremental power to such companies is generally from five to ten times the cost of an equal amount of power to a large utility company.

Industrial plants usually operate, with holidays and other "shut downs" excluded, about forty three hours out of a total of one hundred sixty-eight hours per week. During the remaining one hundred twenty-five

hours of the week, the load on the transformer system is between five and ten per cent of the maximum. In office buildings the ratio of loaded to unloaded operation is about the same. In factories lighting load is superimposed on the daily load for about two hundred hours per year, and this lighting load is about twenty-five per cent of the daily shop operating load. In offices, this lighting load is often equal to one-half of the peak load.

Transformers of known construction designed to produce a low core loss during the large portion of the year when the load is one-tenth or less of the maximum load, are very expensive and not generally used. The transformers commonly used operate with one half per cent core loss and one per cent copper loss.

It is another object of my invention to provide a novel and improved transformer system of the character described which shall be capable of operating at light loads with an extremely small core loss and shall cost less than known types of transformers for similar purposes.

Other objects are to provide such a transformer system including a novel arrangement of transformer windings on the cores, and simple and inexpensive switch mechanism, whereby a number of windings can be operated in series, for example under light load, or in parallel, for example under heavy loads, or as desired; to provide a transformer system of this character having a plurality of high tension coils and a similar number of low tension coils all solidly connected in circuit, and switch means, whereby said coils shall be connected either in series or in multiple without throwing any of said coils out of circuit, and to obtain other advantages and results as will be brought out by the following description.

For the purpose of illustrating the principles of my invention I have shown it in the accompanying drawings embodied in a distribution transformer system which is supplied from the source with a voltage of four thousand and one-hundred fifty volts and steps down the voltage to two hundred forty volts.

Referring to said drawings in which cor-

responding and like parts are designated throughout the several views by the same reference characters,

Figure 1 is a schematic illustration of the transformer system.

Figure 2 is a simplified diagram showing the connection of the transformer windings in series, and

Figure 3 is a similar diagram showing the connection of the transformer windings in multiple.

Specifically describing the illustrated embodiment of the invention the reference character T^1 designates a transformer having a magnetic core 50, and T^2 designates a second transformer preferably mounted in the same tank with the transformer T^1 and having a magnetic core 51. The transformer T^1 has high tension or primary coils 1 and 2 and low tension or secondary coils 3 and 4 wound on the same core.

The high tension coils have the respective terminals 26, 27 and 28, 29 and are connected in series with the high tension or primary coil 5 of the other transformer T^2 which has terminals 30 and 31. The low tension coils 3 and 4 of the transformer T^1 have the respective terminals 32, 33 and 34, 35 and are connected in series with the secondary or low tension coils 6 and 7 of the transformer T^2 . These coils 6 and 7 have a common mid-connection 8 and the respective end terminals 36 and 37. These coils 6 and 7 also have an equal number of turns, and are essentially one winding. In many cases the mid-tap 8 is not necessary, for example, where it is desired to have only one secondary voltage, for example 240 volts, instead of two voltages; 240 v. and 120 v. as shown.

In accordance with the invention, both transformers T^1 and T^2 are designed to operate at very low flux density, and are so designed that with the coils connected in series, the cores will not become saturated until the voltage across the windings has been increased more than three times the normal voltage. This is distinguished from the known modern high efficiency low core loss transformers which are designed to operate at a flux density such that the core will not become saturated up to twice the normal voltage impressed on their windings.

Due to the fact that the high tension transformer coils 1 and 2 have an equal number of turns on a common core, the voltage of these coils will always be substantially equal, and as the coils 3 and 4 also have an equal number of turns, the voltages thereon will always be substantially equal. This is also true of the equal turn coils 6 and 7 which are mounted on a common core 51 whereby substantially equal voltages will be induced in each coil. It should be understood that if the coils 1 and 2 are wound uniformly on the core 50 then the coils 3 and 4 will each be

wound uniformly on the core 50 so that either low tension coil 3 or 4 may operate separately with both high tension coils 1 and 2; in the same manner the coils 6 and 7 will be wound each to have a minimum impedance when operating separately with the primary coil 5.

The coils 1 and 2 have the respective leads 13 and 14 which are connected to the primary leads 19 and 20 over which the current is received at a voltage of four thousand one hundred fifty volts (4,150 v.); and the coils 6 and 7 have the respective leads 11 and 12 which are connected to the secondary lines 10 and 9 across which the voltage is two hundred forty volts (240 v.). Automatic switches 15 and 22 are provided for opening and closing the respective leads 13, 14 and 11, 12, and these switches are shown as having operating solenoids 16 and 23 connected in series with the low tension distribution line 9. The solenoids cooperate with the cores 17 and 24 and the switches are normally influenced into open position by the respective adjustable springs 21 and 25 which may be adjusted to cause the switches 15 and 22 to open and close with approximately one-third load on the distribution line 9.

It should be understood that the closing of the switches 15 and 22 may be accomplished by the use of current transformers in either the primary or secondary power leads, with the secondaries of the transformers actuating the switches. Thus there are two magnetic circuits, one including the primary coils 1 and 2 and their respective secondary coils 3 and 4, and the other including the primary coil 5 and secondary coils 6, 7.

In operation of the system, when it is carrying a light load, the switches 15 and 22 are open so as to leave the coils of the transformers connected in series as above described, and as shown in the simplified wiring diagram, Figure 2. When the load on the system is heavy, or as above described, above one-third the maximum load on the distribution line 9, the solenoids 16 and 23 operate the cores 17 and 24 so as to close the switches 15 and 22 and connect the coils in multiple, as shown by the simplified diagram, Figure 3.

From a study of Figures 2 and 3 it will be observed that at the instant of switching of the windings from series to multiple, the windings 1, 2, 3 and 4 on the core 50 have their voltage increased three times, but the polarity remains the same. On the other hand all of the windings on the core 51 have their voltage increased three times, but their polarity is reversed. Upon a falling off of the load to less than one-third of the maximum load on the line 9, the solenoids are partially deenergized so that the springs 21 and 25 open the switches 15 and 22 and connect the transformer windings in series.

While the greatest economy may generally

be obtained when my invention is utilized in connection with transformers for lighting systems, the savings in connection with an industrial plant over the known types of transformer systems by my invention are considerable. Furthermore, the cost of my transformer system is less than the cost of known types of systems.

Some efforts have been made heretofore to accomplish a result somewhat similar to that obtained by my invention by using two banks of transformers, a small capacity bank operating its core at a very low density and having a high light load efficiency, and another bank of about twice this capacity operating with a high core loss and relatively low copper loss. In such a system, the large transformer is switched on and off as the load varies, and in addition to an interruption of the circuit, the switches must have exactly the same capacity and insulation as used in my system; the switches must rupture against full voltage, i. e. they must have full voltage across them when open, while the switches in my system have only two-thirds voltage across them when open; if the small low core loss transformer of the old system is to operate at as low a core loss as the transformer of my system, the size and cost of the transformer will be substantially the same as the cost of the entire transformer equipment required in my system; and, the large capacity transformer of the old system, if operated at as high a density as is utilized in my system, will be substantially two-thirds as large as the entire transformer equipment used in my system.

It will be manifest to those skilled in the art, that by my invention it is possible to obtain a safer installation with approximately three-fifths of the transformer capacity necessary in heretofore known systems, which is due to the fact that in my system substantially all of the transformer equipment is always used in the most economical manner.

While I have schematically shown the preferred embodiment of my invention, it should be understood that this is primarily for illustrating the principles of the invention, and that the invention may be embodied in many different types of apparatus, and other modifications and changes may be made by those skilled in the art without departing from the spirit or scope of the invention.

Having thus described my invention, what I claim is:

1. A transformer system including a plurality of high tension windings solidly connected together in circuit, a corresponding number of low tension windings solidly connected together in circuit, circuit connections and switch means for throwing said windings from series circuit into multiple circuit when the switch means is respectively open and closed, and means cooperating with said

switch means for closing the latter at heavy load and opening it at light load.

2. A transformer system including a transformer having a core and a pair of high tension windings and a pair of low tension windings thereon, a second transformer having a core and a high tension winding connected solidly in circuit with the high tension windings of the first transformer and a low tension winding having a mid-tap and connected solidly in circuit with the low tension windings on the first transformer, and circuit connections and switch mechanism for throwing all said high tension windings and all said low tension windings respectively from series circuit into multiple circuit.

3. A transformer system including a transformer having a core and a pair of high tension windings and a pair of low tension windings thereon, a second transformer having a core and a high tension winding connected solidly in circuit with the high tension windings of the first transformer and a low tension winding having a mid-tap and connected solidly in circuit with the low tension windings on the first transformer, and circuit connections and switch mechanism for throwing all said high tension windings and all said low tension windings respectively from series circuit into multiple circuit when said switch mechanism is respectively opened and closed, and means controlled by the load upon the secondary leads for closing the switch mechanism at heavy load and opening it at light load.

4. A transformer system including a transformer having a core and a pair of high tension windings and a pair of low tension windings thereon, a second transformer having a core and a high tension winding connected solidly in circuit with the high tension windings of the first transformer and a low tension winding having a mid-tap and connected solidly in circuit with the low tension windings on the first transformer, and circuit connections and switch mechanism for throwing all said high tension windings and all said low tension windings respectively from series circuit into multiple circuit when said switch mechanism is respectively opened and closed, and means controlled by the current in the secondary leads, and means cooperating therewith for closing and opening the switch at a predetermined load upon an increase or decrease respectively in the load.

5. A transformer system including a transformer having a core and a pair of high tension windings and a pair of low tension windings thereon, a second transformer having a core and a high tension winding connected solidly in circuit with the high tension windings of the first transformer and a low tension winding connected solidly in circuit with the low tension windings on the first transformer, and circuit connections and

switch mechanism for throwing all said high tension windings and all said low tension windings respectively from series circuit into multiple circuit.

- 5 6. A transformer system including a transformer having a core and a pair of high tension windings and a pair of low tension windings thereon, a second transformer having a core and a high tension winding connected solidly in circuit with the high tension winding of the first transformer and a low tension winding connected solidly in circuit with the low tension windings on the first transformer, and circuit connections and 10 switch mechanism for throwing all said high tension windings and all said low tension windings respectively from series circuit into multiple circuit when said switch mechanism is respectively opened and closed, and means 15 controlled by the load upon the low tension or secondary leads for closing the switch mechanism at heavy load and opening it at light load.

7. A transformer system including a transformer having a core and a pair of high tension windings and a pair of low tension windings thereon, a second transformer having a core and a high tension winding connected solidly in circuit with the high tension windings of the first transformer and a low tension winding connected solidly in circuit with the low tension windings on the first transformer, and circuit connections and switch mechanism for throwing all said high tension 30 windings and all said low tension windings respectively from series circuit into multiple circuit when said switch mechanism is respectively opened and closed, electromagnetic means controlled by the current in the low tension or secondary leads, and means operating therewith for closing and opening the switch at a predetermined load upon an increase or decrease respectively in the load.

8. A transformer system including an odd 45 number of primary coils for each phase permanently consecutively connected together, a corresponding number of secondary coils for each phase consecutively connected together, two magnetic circuits in each phase, alternate primary coils and corresponding alternate secondary coils being in one said magnetic circuit and the remaining coils being in the other said magnetic circuit, and a switch mechanism in said circuits connected 50 to change from series to parallel circuit all said primary coils and all said secondary coils on closing of the switch mechanism.

9. A transformer system including an odd 60 number of primary coils for each phase permanently consecutively connected together, a corresponding number of secondary coils for each phase consecutively connected together, two magnetic circuits in each phase, alternate primary coils and corresponding alternate 65 secondary coils being in one said magnetic

circuit and the remaining coils in the other said magnetic circuit, and a switch mechanism for controlling said circuits so connected that, upon closing, the voltage across each coil is multiplied as many times as there are primary coils for each phase.

10. A transformer system including an odd 70 number of primary coils for each phase permanently connected in consecutive arrangement and a corresponding odd number of secondary coils for each phase similarly connected, two magnetic circuits in each phase, alternate primary coils and corresponding alternate secondary coils being in one said magnetic circuit and the remaining coils in the other said magnetic circuit, and a switch mechanism for controlling said circuits connected so that upon closing, the second-mentioned coils and the magnetic flux interlacing said coils have their polarity reversed.
